Primary Examiner—Stella Reid*Attorney, Agent, or Firm*—Kane, Dalsimer, Sullivan, Kurucz, Levy, Eisele and Richard[57] **CLAIM**

The ornamental design for an implant for controlling intraocular pressure, as shown and described.

DESCRIPTION

FIG. 1 is a top plan view of an implant for controlling intraocular pressure, showing my new design; FIG. 2 is a cross-sectional view along line 2—2 of FIG. 1;

FIG. 3 is a cross-sectional view along line 3—3 of FIG. 1;

FIG. 4 is a bottom plan view thereof; and, FIG. 5 is a perspective view thereof, the broken line showing of the sclera and eyeball is for illustrative purposes only and forms no part of the claimed design.

FIG. 3

FIG. 1

FIG. 4

FIG. 2

FIG. 5
